UNITED STATES PATENT OFFICE.

GUSTAF IVAR BARCLAY, OF DETROIT, MICHIGAN, ASSIGNOR TO DETROIT STEEL PRODUCTS COMPANY, OF DETROIT, MICHIGAN, A CORPORATION OF MICHIGAN.

WINDOW LATCH.

Application filed May 28, 1923. Serial No. 642,077.

To all whom it may concern:

Be it known that GUSTAF IVAR BARCLAY, a citizen of the United States of America, residing at Detroit, in the county of Wayne and State of Michigan, have invented certain new and useful Improvements in Window Latches, of which the following is a specification, reference being had therein to the accompanying drawings.

10 The invention relates to window latches and is particularly applicable to swinging windows. One of the objects of the invention is the provision of a simple construction of window latch so arranged that the 15 handle will first release the detent and then upon continuation of the force applied to the handle will swing the window to an open position. Another object is the provision of a window latch in which the handle 20 may be used in closing the window and the detent has a swinging movement relative to the handle during the closing so that the locking of the window in closed position does not affect the handle. Further objects of the 25 invention reside in the novel features of construction, combinations and arrangements of parts as more fully hereinafter set forth.

In the drawings:

30 Figure 1 is a side elevation of a window latch embodying my invention and applied to a swinging window construction;

Figure 2 is a bottom plan view thereof partly in section;

35 Figures 3 and 4 are opposite end views thereof;

Figure 5 is a cross section on the line 5—5 of Figure 2.

1 is a swinging window for closing the opening in the frame 2, the side rails of the 40 window sash being pivotally connected near their lower ends to a shoe 3 longitudinally slidably of the frame, 4 is one of a pair of links at each side of the window and pivotally connected to the side rails of its sash intermediate their ends and to the frame 45 near the upper end of its opening. 5 is the supporting bracket of the window latch having the base 6 secured to the inner side of the upwardly extending flange 7 of the top 50 rail of the window sash. This supporting bracket has the horizontally extending bifurcations 8 and 9 extending from the upper and lower edges of the base 4 and through which the pin 10 passes, this pin being non-rotatably secured in the boss 11 of the bi-

furcation 9 by suitable means such as the cotter pin 12.

13 is a swinging handle journalled upon the enlarged end 14 of the pin 10 adjacent to the bifurcation 8 of the supporting bracket, and 15 is a detent journalled upon the reduced end of the pin 10 adjacent to the bifurcation 9 of the supporting bracket, both the handle and detent lying adjacent to each other. The detent extends through the opening 16 in the upright flange 5 of the top rail of the window sash, the base 6 of the supporting bracket being cut away at this point.

17 The free end of the detent has a nose 17 arranged to engage the shoulder 18 upon the locking bracket 19 extending transversely from and secured to the top bar of the window frame 2. The nose 17 of the detent has the inclined bearing surface 20 and the bracket 19 is made preferably half-round whereby upon the swinging of the window to closed position the detent comes into engagement with the holding bracket and is swung in a counter-clockwise direction as shown in 80 Figure 2 owing to the engagement of the inclined bearing surfaces upon the nose of the detent and upon the bracket.

For normally holding the detent 15 in locking engagement with the locking bracket 19 there is the coil spring 21 surrounding the reduced portion of the pin 10 and having its opposite ends respectively secured to the enlarged end 14 of the pin 10 and the detent 15, the arrangement being such that 90 the spring always tends to rotate the detent in a clockwise direction looking at Figure 2. For disengaging the detent 15 from the locking bracket the handle 13 is provided with the lug 22 forming a shoulder engageable with a corresponding shoulder upon the lug 23 with which the detent 15 is provided, the lug 23 extending laterally to overlap the handle and its lug 22. Thus with this arrangement it will be seen that when looking 100 at Figure 2, rotation of the handle 13 in a counter-clockwise direction will, through the lugs 22 and 23, rotate the detent 15 in a counter-clockwise direction to disengage its nose from the shoulder of the locking bracket 19. After disengagement of the detent from the locking bracket further force 105 exerted upon the handle will swing the window to an open position.

For facilitating the closing of the window 110

the handle 13 is provided with the lug 24 engageable with the base 5 of the supporting bracket to limit the rotation of the handle in a clockwise direction looking at Figure 2. Thus with this arrangement, the handle may be gripped to swing the window to its closed position and there is no liability of injuring the fingers by so doing since the handle is prevented from swinging inwardly toward the window beyond its normal position. Furthermore, owing to the fact that the detent is movable relative to the handle it is free to swing outwardly past the locking bracket and then to swing inwardly over the same during the closing of the window without affecting the handle.

What I claim as my invention is:

1. The combination with a support provided with a pin, of a detent mounted upon said pin, a handle also mounted upon said pin, shoulders upon said detent and handle for swinging said detent from said handle upon swinging of said handle in one direction, said shoulders permitting the swinging of said detent independently of said handle, and a coil spring surrounding a portion of said pin for swinging said detent in a direction opposite to that taken when actuated by said handle.
2. The combination with a frame and a closure member movable relative thereto, of a shoulder upon said frame, a supporting bracket upon said closure member provided with a pin, a detent mounted upon said pin and having an inclined nose adapted to have a sliding engagement with said shoulder upon movement of said closure member toward said frame, a handle upon said pin, means for swinging said detent from said handle in a direction to disengage said detent from said shoulder, said means permitting the swinging of said detent independently of said handle when said detent is being swung by engaging said shoulder, means for swinging said detent in the opposite direction, means upon said handle for limiting the swinging of said handle in the opposite direction and a coil spring surrounding said pin and engaging said detent for swinging said detent into engagement with said shoulder.
3. In a window latch, a support, a detent

pivotedly mounted on said support, a lever type handle pivotedly mounted at one end coaxially with said detent, engaging portions formed on said detent and handle adjacent said pivot for swinging said detent through said handle in one direction, but permitting an independent swinging of said detent in the opposite direction.

4. In a window latch, the combination with a sash, of a detent pivotedly mounted thereon, a handle pivoted at one end coaxially with said detent, cooperating portions formed on said detent and the pivoted end of said handle for moving said detent to releasing position through said handle, whereby said detent may be released and said sash moved to open position by a movement of the free end of said handle.

5. In a window latch, the combination with a sash, of a detent pivotedly mounted thereon, a coil spring for yieldably retaining the said detent in locking position a handle pivoted at one end coaxially with said detent, said handle being operable by swinging the free end thereof, cooperating portions formed on said detent and the pivoted end of said handle for moving said detent to releasing position through said handle, whereby said detent may be released and said sash moved to open position by a movement of the free end of said handle.

6. In a window latch, the combination with a sash, of a detent pivotedly mounted thereon, a handle pivoted at one end coaxially with said detent, cooperating portions formed on said detent and the pivoted end of said handle for directly actuating said detent during the movement of the handle in one direction, said handle being operable by swinging the free end thereof.

7. In a window latch, a support, a detent pivotedly mounted on said support, a handle pivoted at one end co-axially with said detent, cooperating portions formed on said detent and the pivoted end of said handle for moving said detent to releasing position through said handle, and a spring housed within said handle and connected to said detent for normally retaining said detent in locking position.

In testimony whereof I affix my signature.

G. IVAR BARCLAY.
